INVENTOR
ARTHUR W. PARMELEE.

BY *Rufus D. Fowler*

ATTORNEY.

UNITED STATES PATENT OFFICE.

ARTHUR W. PARMELEE, OF WORCESTER, MASSACHUSETTS, ASSIGNOR TO
THE WIRE GOODS COMPANY, OF SAME PLACE.

COAT AND HAT HOOK.

SPECIFICATION forming part of Letters Patent No. 640,935, dated January 9, 1900.

Application filed July 1, 1898. Serial No. 684,930. (No model.)

To all whom it may concern:

Be it known that I, ARTHUR W. PARMELEE, of the city and county of Worcester, in the Commonwealth of Massachusetts, have invented certain new and useful Improvements 5 in Wire Coat and Hat Hooks, of which the following is a specification, accompanied by drawings forming a part of the same, in which—

Figure 1 represents a perspective view of 10 one of my improved hooks. Fig. 2 is a perspective view of the hook with the wall-plate removed, and Fig. 3 is a front view.

Similar letters refer to similar parts on the different figures.

15 My invention relates to that class of coat and hat hooks which are made from a single piece of wire doubled upon itself to form the upper and lower hooks and provided with a screw-threaded end by which the hook is attached to the wall.

20 My improved hook is made from a single piece of wire having a screw-thread *a* formed upon one end adapted to be screwed into the wall, and when the hook is in position the 25 wire extends horizontally from the wall the requisite distance and is then turned upwardly to form the upper hook *b*. It is then bent sidewise and back parallel to itself in the form of an elongated loop *b'*. The two 30 parts *c* and *d* of the wire are twisted together at *e* about midway between the screw-threaded end *a* and the hook *b*. The part *d* is bent downward in a semicircular curve *f* and back upon itself at *g*, forming an elongated loop 35 *h*, which constitutes the lower hook *i*, with the end *j* of the wire terminating about midway the semicircular curved portion *f*.

40 *k* denotes a wall-plate, preferably cut from ductile sheet metal and having a hole *k'* to receive the screw-threaded end of the wire. The wall-plate *k* extends downwardly and is provided at the lower end with two lateral lugs or wing-pieces *l l*, which are bent forward and over the end *j* of the wire and the semi-45 circular curved portion *f*. The lugs *l* serve to unite the curved portion *f* of the hook and the free end *j* of the wire and connect both with the horizontal straight portion of the wire next the screw-threaded section *a*. I 50 thereby secure a double wire, forming an elongated loop in the lower hook, providing

a broad supporting-surface similar to that afforded by the upper hook, with an oblique brace formed by the curved section *f* of the lower hook, which strengthens the hook where 55 it enters the wall, and I secure the free end *j* of the wire to the wall-plate, which prevents the distortion of the lower hook and improves the appearance of the completed hook.

I am aware that the combination of a wall-60 plate with a wire hook having a lower hook curved to form an oblique brace is not new. Neither is it new to twist together the two parts of the wire which form the upper hook, and I do not claim either of these features 65 broadly. Neither do I claim the use of a wall-plate connecting the upper and lower hooks, for such a wall-plate was shown in Letters Patent of the United States No. 392,222, issued to me November 6, 1888; but in my present hook the curved section *f* of the lower hook is utilized as a brace between the wall-plate and the center or intertwined portion 70 of the upper hook, so that the resistance of the brace will be applied to the central portion of the upper hook and a short distance from the wall-plate, thereby increasing the strength of the hook at its weakest point, or where it enters the wall.

75 While I prefer to make the upper and lower hooks in the form of elongated loops, as described, I do not confine myself to any particular form of upper or lower hooks, as they may be changed, if desired. The intertwisting of the two parts of the wire forming the 80 upper hook at the central section thereof is for the purpose of securing the joint resistance of both wires to a strain applied to the upper hook and also to secure the bracing action of the curved section of the lower hook 85 at the central portion of the upper hook, and it is obvious that the two parts of the wire forming the upper hook may be united by other means than twisting and secure the same results. Therefore I do not confine myself to twisting the wire in the upper hook.

90 What I claim as my invention, and desire to secure by Letters Patent, is—

95 The within-described coat and hat hook, comprising an upper and a lower hook and 100 consisting of a single piece of wire provided at one end with a screw-thread *a*, adapted to

be screwed into the wall, said wire extending horizontally from said screw-threaded end, when the hook is in position of use, and being bent upon itself to form an elongated loop *b'*, with its end turned slightly upward to form an upper hook *b*, with the two sides *c*, *d*, of the loop twisted together at *e*, about midway between the hooked end *b* and the screw-threaded end *a*; the side *d* being bent downward in 5 a semicircular curve *f* and bent back upon itself at *g*, forming an elongated loop *h* bent in semicircular form and constituting the lower hook *i*, with the other end *j*, of the wire, terminating about midway the semicircular 10 curved portion *f*, and a wall-plate *k* having a 15

hole *k'* by which it is strung upon the straight screw-threaded end of the wire, said wall-plate having at its lower end two lugs, or wing-pieces, *l*, *l*, bent over the end *j* of the wire and also over the curved portion *f*, thereby uniting the end *j* of the wire to the curved portion *f* and also uniting the central portion of the curved portion *f* to the straight horizontal screw-threaded section, substantially as described. 20

ARTHUR W. PARMELEE.
